(57) **CLAIM**

We claim the ornamental design for charger for a lighting device, as shown and described.

DESCRIPTION

FIG. 1 is a perspective view of the charger for a lighting device of the design.

FIG. 2 is a right side view of the charger for a lighting device of the design. A left side view is a mirror image of the right side view.

FIG. 3 is a front view of the charger for a lighting device of the design.

FIG. 4 is a back view of the charger for a lighting device of the design.

FIG. 5 is a top view of the charger for a lighting device of the design; and,

FIG. 6 is a bottom view of the charger for a lighting device of the design.

Any broken line(s) shown are for illustrative purposes only and form no part of the claimed design.
